SURGEON'S SCRUB SINK

Thomas Brendgord, Erie, Pa., assignor to American Sterilizer Company, Erie, Pa.

Filed Aug. 18, 1970, Ser. No. 24,558

Term of patent 14 years

Int. Cl. D23—92

U.S. Cl. D23—58

FIG. 1

FIG. 2

FIG. 1 is a perspective view taken from one end of a surgeon's scrub sink embodying my new design, the opposite end being a mirror image of the end shown; and

FIG. 2 is an other perspective view thereof. The bottom and rear of the sink are plain.

I claim:

The ornamental design for a surgeon's scrub sink, as shown and described.
